[57] CLAIM

The ornamental design for a hay wagon having front and rear extensions for supporting feed or watering containers, as shown and described.

DESCRIPTION

FIG. 1 is a front and top perspective view of the hay wagon having front and rear extensions for supporting feed or watering containers showing my new design;

FIG. 2 is a front view thereof;

FIG. 3 is a rear view thereof;

FIG. 4 is a side view thereof; and,

FIG. 5 is a top plan view thereof.

The hitch shown in FIGS. 1, 4 and 5 and the wagon shown in FIGS. 4 and 5 are shown broken away for convenience of illustration.

FIG. 4

FIG. 5

FIG. 3
